UNITED STATES PATENT OFFICE.

GEORGE H. OTTO, OF HERMANN, MISSOURI.

SHOE-INKER.

1,190,947.

Specification of Letters Patent.

Patented July 11, 1916.

Application filed February 5, 1916. Serial No. 76,438.

To all whom it may concern:

Be it known that I, GEORGE H. OTTO, a citizen of the United States, residing at Hermann, in the county of Gasconade and State of Missouri, have invented certain new and useful Improvements in Shoe-Inkers; and I do hereby declare the following to be a full, clear, and exact description of the invention, such as will enable others skilled in the art to which it appertains to make and use the same.

This invention relates to new and useful improvements in a shoe inker and one of its objects is the provision of a device of this character, which shall be simple, durable and efficient and which may be manufactured and sold at a comparatively low cost.

Another object of this invention is to provide a tank or reservoir for containing inking or blackening fluids and having mounted on the lower end a receptacle to receive the head of a brush and to receive the inking or blackening fluid from the reservoir to evenly distribute the fluid upon the brush.

Another object of this invention is to provide a valve rod, having a valve thereon and which extends through the reservoir or tank and receptacle and threaded into an engagement with the brush for regulating the flow of inking or blackening fluid upon the brush.

Another and more specific object of this invention is the provision of a spring attached to the valve rod and to the reservoir or tank to hold the valve in a seated position until pressure is placed upon the brush to compensate for the tension of the spring, whereby the valve will be unseated and allow the inking or blackening fluid to pass out of the tank or reservoir upon the brush through the receptacle.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which:

Figure 1 is a front elevation of a shoe inker constructed in accordance with my

invention, Fig. 2 is a vertical sectional view 55 of the tank or reservoir and receptacle, illustrating the valve in a seated position, Fig. 3 is a longitudinal sectional view taken on the line 3—3 of Fig. 2, looking in the direction indicated by the arrows, and Fig. 4 is a vertical sectional view similar to Fig. 2, illustrating the receptacle spaced from the tank and in a position to allow the valve to move to an open position when pressure is placed upon the brush.

Referring in detail to the drawing, 1 indicates a substantially funnel shaped tank or reservoir, having a cover 2 screw-threaded to the upper end thereof. The cover 2 is provided with a filling opening 70 adjacent one edge and receives a stopper or cork 3, which may be readily removed when desiring to fill the tank or reservoir 1 with inking or blackening fluid. The cover 2 is further provided with a central aperture to 75 receive a valve rod 4, having a handle 5 secured to the upper end thereof. The valve rod 4 is screw-threaded between the cover 2 and the handle 5 as illustrated at 6 and has mounted thereon a collar 7 for travel 80 upon the screw-thread 6 of the valve rod 4. Surrounding the valve rod 4 is an expansion spring 8 provided with one of its ends secured to the collar 7 and its other end secured to the cover 2. Formed on the lower 85 end of the valve rod 4 is an internally screw-threaded sleeve 9, having a shoulder 10 on the upper end thereof. A rubber valve washer 11 is mounted on the sleeve 9 and held thereon by the shoulder 10. The periphery 12 of the valve washer 11 is beveled to conform with the contour of the funnel shaped walls 13 of the tank or reservoir 1.

A substantially funnel shaped receptacle 14 is adapted to receive the lower end of 95 the tank or reservoir 1 in its enlarged upper end. The lower end of the receptacle 14 is provided with an elongated member 15, having downwardly extending flanges 16 formed on the edges thereof, to receive a 100 brush which will be hereinafter more fully described.

An elongated brush head 17 has secured thereto a plurality of bristles 18 in any well known manner and positioned upon the 105 brush head 17 is a plate 19 provided with its ends bent downwardly into an engagement with the ends of the brush head to

firmly hold the plate 19 upon the brush head 17. Formed centrally of the plate 19 is a stud 21 which has secured thereto an externally screw-threaded pin 22 which is threaded into the sleeve 9 for attaching the brush to the valve rod 4 and within the member 15. The brush head 17 is provided with slots 23 on each side thereof to allow the inking or blackening fluid to pass outwardly upon the brush head 17 from the reservoir 1.

In operation the tank or reservoir 1 is filled with inking or blackening fluid and the receptacle 14 is rotated in one direction 15 until the receptacle 14 assumes a position as illustrated in Fig. 4, providing a space between the walls of the receptacle and the tank or reservoir 1 and as the receptacle is rotated in the direction above mentioned, 20 the brush will be rotated and the pin carried by the brush head will be unscrewed part way from the sleeve, causing the brush to move away from the valve 11. By pressing the brush upon a shoe it will cause the receptacle and valve to move upwardly and allow the inking or blackening fluid within the tank or reservoir 1 to pass into the receptacle and then outwardly through the slots 23 upon the bristles 18 of the brush 25 head. As soon as the pressure is released upon the brush the valve 11 will automatically seat itself by the tension of the spring 8 and the inking or blackening fluid which is upon the brush and within the receptacle 30 may be then spread upon the shoe without further inking or blackening fluid passing outwardly from the tank or reservoir 1. When a thick or thin liquid is used in this device, the outflow of the liquid may be 35 easily and quickly regulated by turning the receptacle in one direction or in the opposite direction depending which kind of liquid is being used to move the brush head and receptacle away and toward the tank or 40 reservoir 1, to regulate the upward movement of the valve 11, when pressure is placed upon the brush. After inking or blackening a shoe and not desiring to use the device, the receptacle 14 is rotated in a 45 clockwise direction causing the receptacle to move into tight engagement with the tank or reservoir 1 and when in this position the brush will have been rotated in a closer relation to the valve 11, completely 50 cutting off the flow of liquid from the tank or reservoir 1. The device then may be 55 handled by a child or unskilled person without the danger of the inking or blackening fluid wasting from the tank or reservoir 1 60 if the child or unskilled person was to exert pressure upon the brush.

While I have shown and described the preferred embodiment of my invention, it will be understood that minor changes in 65 construction, combination and arrangement

of parts may be made without departing from the spirit and scope of the invention as claimed.

Having thus described my invention, what I claim is:—

1. A shoe inker comprising a substantially funnel shaped tank, a substantially funnel shaped receptacle rotatably mounted upon said tank, a cover detachably secured to said tank, a valve rod mounted in said cover and extending through the tank and terminating at a point adjacent the lower end thereof, a valve secured to the lower end of the valve rod for an engagement with the walls of the tank, said valve rod provided with its upper end screw-threaded, a collar mounted on said valve rod for traveling upon the screw-threads, a spring surrounding the valve rod and provided with one of its ends secured to the collar and its other end secured to the cover for normally holding the valve in a seated position, a brush head received by the lower end of the funnel shaped receptacle, and means for adjustably securing the brush to the lower end of the valve rod to regulate the upward movement of the valve.

2. A shoe inker comprising a substantially funnel shaped tank, a substantially funnel shaped receptacle rotatably mounted upon said tank, a cover detachably secured to said tank, a valve rod carried by said cover and extending through the tank to a point adjacent the lower end, a sleeve secured to the lower end of the valve rod, a shoulder formed on the upper end of said sleeve, a rubber washer mounted on said sleeve for an engagement with the walls of the tank and held thereto by means of said shoulder, a brush head carried by the lower end of said measuring receptacle, and means for adjustably securing the brush to the sleeve for regulating the upward movement of the rubber washer when pressure is exerted upon the brush.

3. A shoe inker comprising a substantially funnel shaped tank, a substantially funnel shaped receptacle rotatably mounted on the tank, a valve rod extending into said tank and terminating at a point adjacent the lower end thereof, means for detachably securing the valve rod to the tank, a sleeve secured to the lower end of said valve rod, a shoulder formed on the upper end of said sleeve, a rubber washer mounted on said sleeve and held thereon by said shoulder for an engagement with the walls of said tank, said sleeve provided with an internally screw-threaded opening, and an elongated member formed on the lower end of said receptacle, flanges formed on said elongated member, a brush received by said elongated member within said flanges, and means for adjustably securing the brush to the internally screw-threaded opening of said sleeve

for regulating the upward movement of the rubber washer when pressure is exerted upon the brush.

4. A shoe inker comprising a substantially funnel shaped tank, a substantially funnel shaped receptacle rotatably mounted upon said tank, a valve rod extending into said tank and terminating at a point adjacent the lower end thereof, means for detachably and 10 adjustably securing the valve rod to the tank, a sleeve secured to the lower end of said valve rod, a shoulder formed on the upper end of said sleeve, a rubber washer mounted on said sleeve and adapted to abut 15 the shoulder, said washer provided with its periphery beveled to conform to the contour of the walls of said tank, an elongated member formed on the lower end of said receptacle, flanges formed on said elongated member, 20 a brush received within the flanges of said elongated member, and means for adjustably securing the brush head to the sleeve for regulating the upward movement of the rubber washer when pressure is exerted 25 upon the brush.

5. A shoe inker comprising a tank, a receptacle rotatably mounted on said tank, a valve rod adapted to extend into said tank and terminating at a point adjacent its lower 30 end thereof, means for detachably and adjustably securing the valve rod to said tank, a valve secured to the lower end of said valve rod for an engagement with the walls of said tank, an elongated member formed 35 on said receptacle, a brush received by said elongated member, a plate secured to said brush, a screw-threaded pin secured to said plate and screw-threaded to said valve for regulating the upward movement of the 40 valve within the tank when pressure is inserted upon the brush.

6. A shoe inker comprising a tank, a receptacle rotatably mounted on the lower end of said tank, a valve rod adapted to extend 45 into said tank and terminate at a point ad-

jacent its lower end, means for detachably and adjustably securing the valve rod to said tank, a valve carried by the lower end of said valve rod, an elongated member formed on the lower end of the receptacle, flanges 50 formed on said elongated member, a brush received within the flanges of the elongated member, a plate mounted on said brush and provided with its ends bent downwardly into an engagement with the ends of the 55 brush, a screw-threaded pin secured to said plate and adjustably secured to the valve for regulating the upward movement of said valve within the tank, said brusher provided with recesses on each side thereof to allow 60 inking fluid to pass outwardly from the measuring receptacle to the brush.

7. A shoe inker comprising a substantially funnel-shaped tank, a substantially funnel-shaped receptacle rotatably mounted on the 65 reduced lower end of the funnel-shaped tank, a cover detachably secured to the upper end of the tank, a valve rod adjustably secured to the cover and extending into the tank, a sleeve secured to the lower end of the 70 valve rod, a valve secured to the sleeve, an elongated member formed on the lower end of the receptacle, downwardly extending flanges formed on the sides and ends of the elongated member, a brush slidably mounted 75 within the flanges and provided with slots on each side thereof, a plate positioned on the brush and provided with its ends bent downwardly into an engagement with the ends of the brush, an internally screw-threaded stud formed centrally of the plate, a screw-threaded pin threaded to the stud and sleeve for adjusting the upward movement of the valve within the tank.

In testimony whereof I affix my signature 85 in presence of two witnesses.
